UNITED STATES PATENT OFFICE.

WYMAN DEARBORN, OF BOSTON, ASSIGNOR TO F. ROCKWOOD HALL, OF BROOKLINE, MASSACHUSETTS.

COTTON-GIN.

SPECIFICATION forming part of Letters Patent No. 340,294, dated April 20, 1886.

Application filed August 11, 1884, Serial No. 140,236. Divided and this application filed May 27, 1885. Serial No. 166,810.
(No model.)

To all whom it may concern:

Be it known that I, WYMAN DEARBORN, of Boston, in the county of Suffolk and State of Massachusetts, a citizen of the United States, 5 have invented a new and useful Improvement in Cotton-Gins, of which the following is a full, clear, and exact description, reference being had to the accompanying drawings, forming a part of this specification in explaining its nature, in which—

Figure 1 is a vertical section. Fig. 2 is a plan of the machine. Fig. 3 is an enlarged view of the roll. Fig. 4 is an enlarged detail of the wear adjustment for the boxes of the 15 slotted arms.

This invention is a subdivision of the application for a patent for improvement in picker-feed cotton-gins, filed August 11, 1884, and numbered 140,236, and relates to the cotton-gin part of the machine therein described.

The drawings illustrate the complete machine, and the parts lettered with large and small letters and numbered letters from A to K inclusive, and R and S are the parts described in the specification from which this has been separated, and are shown described, and some of the novelties of them patented in Letters Patent of June 16, 1885, No. 319,964.

The drawings illustrate a picker-feed cotton-gin, or a cotton-gin in which cotton is picked and cleaned before being fed to the gin proper, in which the seeds are removed.

The whole machine is described in the other application, and the cotton-gin part only will be described in this.

The gin proper, to which this specification relates, may be a roller-gin or may be a belt-gin, which latter type of gin was patented to Bracket and Dearborn, March 22, 1867, No. 63,136. The belt of the Bracket and Dearborn patent is for the purpose of cleaning cotton, the mechanical equivalent of a roll, and differs from it only in the fact that it may have a quicker, stronger, and longer grasp of the cotton-fiber, and is more thoroughly aerated in each revolution and for a longer time than a roll of the same curvature of the sharpest curvature of the belt, or even than a roll of the same superficial size; hence what will be said concerning the roll of the gin in this speci-

fication is clearly applicable to a belt of the Bracket and Dearborn type. The roll L is situated abreast of the extremity of the feed-table F, and the presser-bar l is placed somewhat below the roll and between it and the extremity of the feed-table. In this space between the roll and the feed-table vibrate the clearers l² l³. Seed-cotton is fed from the feed-table over the lower clearer and presser-bar to the roll, and is caught by the drawing-surface of the roll and drawn between the roll L and the presser-bar l, while the clearer l³, in its descent, detaches the seed from the fiber, and the clearer l², as it rises, lifts the seeds up past the edge of the presser-bar, and so gives the roll a better chance to engage with the cotton-fiber than it would have were this clearer l² not present, particularly when the cotton is short staple or staple of moderate length.

It is true that clearers having double blades have been heretofore employed; but in these the lower blade has been provided with saw-teeth, and was adapted to tear or comb the seed from the fiber; or, if it were a smooth-edged blade, as in the double clearer patented by Greaves in England, (No. 3,526 of 1871,) the two blades were so adjusted that they each passed the upper edge of the presser-bar in their reciprocation about an equal distance, the lower blade going up above the edge of the presser-bar as far as the upper blade in the return-stroke passed below the same point. In this mechanism the lower blade, l³, has a smooth edge, as the Greaves lower blade had, and it can be seen by the position and throw of the crank (shown and indicated in the drawings) that the lower edge of the upper blade will pass in the downstroke the upper edge of the presser-bar about twice to three times as far as the upper edge of the lower blade passes the same line in its upward stroke; hence the lower blade of this clearer is not a doffing-blade like the upper one, but only to lift the seeds upward so as to bring the fiber attached to them in contact and engagement with the surface of the revolving roll L, and thus give the roll a better hold on the fiber, or a better chance to engage with the fiber.

The work of knocking the seed out against the upper edge of the presser-bar L is done

entirely or almost entirely by the upper blade, l^2 , as is customary in roller-gins. This upper blade, l^2 , should be, as usual, adjustable. The cotton thus falls on the roll side of the presser-bar l into a chamber, M , and the clean seeds fall on the other side of the presser-bar into or toward the chamber N , the two chambers, M and N , being separated by a partition, m .

Below the clearers $l^1 l^2$ is placed a separator. 10 This may be a screen, O , the meshes of which are not large enough to allow seeds carrying any considerable quantity of cotton to pass through, but are large enough to allow seeds entirely clean to pass through; hence clean seeds only will be collected in the chamber N , and the cotton-carrying seeds will be left above the screen O ; and such a separator as this should be slightly agitated during the working of the gin, and generally will get agitation 15 enough from the vibration of the machine.

Instead of this screen-separator there may be placed in the chamber N a revolving separator, P , which has a barrel made with open meshes, which meshes are large enough for 20 clean seeds to drop through them past the shaft, and not large enough to allow seeds carrying any considerable quantity of cotton to pass through. This separator P has upon its exterior wings p , and revolves slowly toward 25 the partition m . It will be seen that seeds clean of cotton will, as they fall, strike either on the open-work barrel or wings p , and if clean will drop through the separator P , and through the chute placed below it (but not 30 illustrated) into a chamber below the separator P , while the seeds carrying cotton will be carried forward and deposited in that part of the chamber N which is close to the partition m . Thus, if the fixed screen O is used it 35 acts as a stationary separator, while if the revolving separator P is used, it acts as a moving separator. These separators and their position are described that the whole machine may be understood and the relation of all the 40 parts, but no claim of invention or monopoly is made on them.

In order to provide for wear in the slotted arms Q of the clearers, I line the slots in which the crank-pins of the crank-shaft which 45 moves these slotted arms reciprocates in boxes, with gibs q , (which are adjustable to and from the crank-boxes by means of set-screws q^1 , which have their nuts in the frames around the slots, and which have their points resting on the gibs q , whereby the gibs q may be forced inward,) and drawing-screws q^2 . These drawing-screws q^2 are driven into the gibs, and draw them away from the boxes, and in order that this draft may be in some 50 degree self-adjusting, I place under the heads of the screws q^2 spring-washers q^3 , of rubber

or other resilient material—such as coiled springs—whereby a constant pressure to draw the gibs away from the boxes is exerted, and a very delicate and fine adjustment may be 55 made.

The drawing-screws q^2 may have their nuts in the gibs and be headed at the upper ends, or may have screws cut in their upper ends and nuts run on them above the washers.

The novel combination here is the movable gib set in position and held there by spring drawing-screws and by set-screws.

The roll-surface which I prefer (and a similar surface is desirable for the belt-type 75 of gin if it be used) is a ribbon of rubber-duck but slightly rubbered and wound spirally in several thicknesses about and securely fastened to a shaft of wood or other proper material. It is better to have the ribbon of several 80 plies of duck, and the edges of the spirally-wound ribbon should not abut closely, but should be slightly separated from each other. This is shown in Fig. 3, where L' represents the ribbon and L^2 the wooden shaft. The 85 working-surface of this roll is to be a canvas surface rather than a surface of india-rubber; but this canvas surface is to be saturated with india-rubber and vulcanized, without, however, interfering with the ordinary roughness 90 of the canvas or duck. This roll, again, as well as the separator, is not a subject of the invention claimed in this application, but is described here as the best form of roll contemplated for use.

The parts of the invention shown in the drawings and not herein described will be found described in the other application from which this has been divided.

Having thus fully described my invention, 100 I claim and desire to secure by Letters Patent of the United States—

1. The combination, with the feed-table, presser-bar, and roll of a cotton-gin, of the smooth-edged clearers $l^1 l^2$, whose motion past the line of the upper edge of the presser-bar l is regulated to compel and allow the clearer l^2 in its downward throw to descend past the said upper edge of the bar l a distance twice 105 as far, or more, than the clearer l^1 ascends above the line of the upper edge of said presser-bar l in its upward throw, substantially as described.

2. The combination of the gibs q , set-screws q^1 , drawing-screws q^2 , and spring-washers q^3 115 with the slotted clearer-arms and crank-boxes of a cotton-gin, substantially as described.

WYMAN DEARBORN.
